JIG SAW PUZZLE

Minnie E. Noble, Berkeley, Calif.

Application September 28, 1932, Serial No. 635,164.

3 Claims. (Cl. 273—157)

The invention relates to jig saw puzzles and more particularly to the construction of the blank of material from which the sections of such puzzles are made.

8. An object of the invention is to provide a puzzle of the character described having the various sections thereof flexible and compressible so as to permit compression especially of certain sections defining the inner portions of the pattern 10 to facilitate their insertion in and withdrawal from openings defined by adjacent sections and also to permit distortion and undue strains without danger of mutilating or permanently damaging the sections.
12. Another object of the invention is to provide a puzzle of the character described in which the aforesaid sections are of such lightness and softness as to permit the placing of the puzzle at the disposal of a small child with absolute safety not only to the child but also to the surrounding objects which would, with the sections otherwise constructed, be subject to scratching or breakage incurred by throwing or rubbing of the sections thereagainst.
25. A further object of the invention is to provide a puzzle of the character described which is formed from a blank of material which may be readily severed such as by means of a household knife or scissors whereby the blank may be cut into a desired plurality of complementary sided configurations for assembly, the blank having indicated thereon different cutting patterns any of which may be selected so that the complexity of said configurations may be left to the discretion of the purchaser and chosen in accordance with the intellectual development of the user.

The invention possesses other objects and features of advantage, some of which, with the fore- 40 going, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a plan view of the puzzle with the sections uncut.

Figure 2 is a sectional view of the puzzle with the sections cut, the plane of the section being taken substantially on the line 2—2 of Figure 1.

Figure 3 is a perspective view of one of the sections of the puzzle.

Figure 4 is a bottom view of the puzzle on a smaller scale.

Referring more particularly to the drawing, the puzzle of my invention comprises a blank 6 including a body portion 7 formed of a soft and elastic material, such as rubber, and a flexible inelastic cover 8 such as paper or cloth or the like which is secured over the upper side of the portion 7 and is provided on its exposed side with a suitable picture 9. The flexible yet inexpensive 10 cover cooperates effectively with the elastic rubber body portion not only to produce a soft, flexible and compressible structure but to hold the body portion against permanent distortion caused by breaking down or weakening of the rubber 15 fibres. In certain instances, if desired, the cover 8 may be omitted and a figure printed directly on the surface of body portion 7. However, due to its unique functioning in combination with the body portion as aforesaid, and its better 20 adaptability for receiving a print than the soft, pliable surface of the rubber body portion, a cover of the character described is desirably included.

The rubber body portion by reason of its softness and compressibility may in accordance with 25 my invention assist materially in the assembly of the various sections of the puzzle. For instance it frequently occurs that several sections may be assembled about a space identified by a missing section and it is necessary to insert the missing 30 section when found so that the same will engage over its periphery with the several already positioned adjacent sections. Where the joining lines between the sections are formed along rather complexe curves, it will be understood that entry 35 of a section into its allotted space is difficult without upsetting or at least partially deranging the adjacent properly positioned sections. Especially is this so where, as with the puzzles heretofore available, the sections have been 40 made of an unyielding material such as wood or cardboard in which case considerable jostling between the sections is often necessary to position an entering section. In accordance with my invention, however, the sections by reason of their 45 softness and resiliently yieldable nature permit of a slight compression of an entering section to afford entry thereof into an opening without contacting and thereby deranging the adjacent sections, and when released will uniformly expand 50 into proper engagement with and without disturbing, the adjacent sections.

As an important feature of the invention I provide a blank of the character described which may be cut by the purchaser to a plurality of 55

complementary sided sections 12 which when operatively assembled are arranged to interfit one with the other to form a continuous exposed surface including the cover 8 in its entirety and also 5 in its original form whereby the picture provided thereon will be formed. In order to facilitate the cutting out of the sections by the purchaser, the rear surface 14 of the blank is preferably formed with lines or otherwise marked to 10 indicate to the user a pattern for cutting the sections. Referring to Figure 4, I have illustrated in the puzzle shown three of such patterns, one in light full lines 16 indicating a simple rectangular arrangement of the sections, one in heavier full lines 17 indicating a more complicated 15 configuration of the sections, and one in dotted lines 18 indicating a still more complicated pattern for cutting the sections, the latter pattern being also indicated in dotted lines in Figure 1. 20 The location of such patterns on the side of the blank opposite the cover 8 enables the use of a plurality of patterns without having the latter visible when the sections are operatively arranged. It has also been found that the provision of the 25 patterns on the bottom side of the blank greatly facilitates the proper cutting of the sections, especially when such cutting is effected by means of the knife or other sharpened blade for the inelastic cover provides a firm and immovable 30 base against which the pliable elastic rubber body portion of the blank may be precisely cut.

While it will of course be clear that the puzzle may, if desired, be merchandised with the sections already cut apart, it is desirable, in the interests of providing a more delightful and intriguing game puzzle, to leave the cutting of the sections to the purchaser so that the complexity of the puzzle may be better adapted to the user. In either event it will be clear that with the sections 40 thus formed of the inexpensive covering in combination with the elastic body as here disclosed will be soft, flexible and light and at the same time have sufficient resiliency to insure a reten-

tion of the sections in coplanar relation when operatively assembled on a smooth surface.

I claim:

1. In a puzzle of the character described, a blank of soft compressible rubber or the like arranged for cutting into a plurality of odd-shaped sections for assembly, and a figured cover of substantially inelastic material secured to one side of said blank and serving to hold the blank fibers adjacent the cover against transverse distortion 10 for cutting of the blank and as an inelastic base against which the blank may be cut. 5

2. A jig saw puzzle comprising, a plurality of interfitting sections forming when properly assembled a continuous surface, said sections being formed of a compressible material to permit of the entry of a section into engagement with adjacent and positioned sections by compressing the entering section sufficiently to allow entry thereof without disturbing the positioned sections and then releasing the entering section for expansion into engagement with the adjacently positioned sections. 15

3. In a puzzle of the character described, a plurality of interfitting sections each comprising, a soft compressible rubber body, and an inelastic cover secured to said body and provided with a figured outer surface forming a part of a composite picture whereby the sections when properly assembled will cause said individual covers 25 notwithstanding said compressible bodies to form a continuous inelastic surface displaying said composite picture, said section bodies being formed of a compressible material to permit of the entry of a section into engagement with adjacent 30 and positioned sections by compressing the entering section sufficient to allow entry thereof without disturbing the positioned sections and then releasing the entering section for expansion into engagement with the adjacent positioned sections. 35 40
